MAGNETO

Walter Ochsenbein, Berne, Switzerland, assignor
to Hasler A.-G. Werke für Telephonie und
Präzisionsmechanik, Berne, Switzerland

Application May 12, 1944, Serial No. 535,358
In Switzerland June 28, 1943

3 Claims. (Cl. 171—209)

The present invention is an improvement in and relating to a magneto, and more particularly to the circuit breaker apparatus for the ignition.

Heretofore, in magnetos incorporating, in the casing of the magneto, a circuit breaker apparatus, which comprises at least one cam wheel and one circuit breaker lever, it has been impossible to withdraw the circuit breaker as a whole body from the casing for controlling the timing contacts, so that it has been extremely difficult to adjust the parts relative to one another for obtaining a mechanically perfect working.

With a view of overcoming these difficulties the present invention proposes to mount all parts belonging to the circuit breaker apparatus upon a common support which is fitted into the casing of the magneto on the side of the cover plate, so that the whole circuit breaker apparatus, including the cam wheel, can be withdrawn together with said support from the casing.

The accompanying drawing illustrates one embodiment of the invention.

Fig. 1 is a longitudinal section of that part of the magneto which comprises the circuit breaker.

Fig. 2 shows a frontal view from the right side in Fig. 1 of the circuit breaker apparatus, when withdrawn from the casing.

Reference character 1 denotes the casing of the magneto, 1a a pot-like casing insertion and 3 the hollow rotor shaft of the magneto, which extends through the intermediary wall 1' of the casing into the casing insertion 1a. Between the wall 1' and the pot bottom of the casing insertion 1a there is disposed the distributor disc 4 with a conductor piece 5 traversing the same and co-operating with the electrodes 6 and 7. The distributor disc 4 is detachably secured to a coupling sleeve 8 which is removably mounted on the rotor shaft 3. The casing 1 has (in Fig. 1 on the left side) a cover plate consisting of two parts, i. e. a peripheral part 9 and a central part 10. Upon the inner side of the cover part 10 there is fixed by means of screws 11 a disc 12 which is the support for all the parts belonging to the circuit breaker apparatus. The disc 12 has a central hollow nave 13 which projects inwardly and carries a bush 14. This bush 14 supports by means of roller bearings 15 a rotatable sleeve 16 forming a double cam wheel. The ring 17 upon the end of the nave 13 is to prevent bush 14 and cam sleeve 16 from slipping off the nave. Cam sleeve 16 and coupling sleeve 8 engage each other by means of claws, so that upon rotation of shaft 3 and sleeve 8 the cam sleeve 16 is driven. The 55

disc 12 has inside in diametrically opposite places two brackets 18 which carry each a pin 19 and a circuit breaker lever 20. On two other diametrically opposite places of the disc 12 are mounted two coil condensers which, in known manner, are in parallel connection with the circuit breaker contacts. In order to adjust the cam sleeve 16 in relation to the circuit breaker levers and to adjust said levers in relation to the stationary contact 22 fixed to the disc 12, the cover part 10 together with the disc 12 and the whole circuit breaker apparatus can be withdrawn from the casing after the screws 11 have been unscrewed. This adjusting and controlling work can be done in a suitable place and position, for instance upon a table.

In Fig 1, on the left side, it is indicated in dotted lines, that a rod 23 which is slidably disposed in the hollow shaft 3 may extend through the cover part 10 for being engaged by a lever (not shown) whereby, for instance, the timing of the ignition may be adjusted.

What I claim is:

1. In combination with a magneto having a casing, a cover plate arranged on one side of said casing, a coupling sleeve fitted on the rotor shaft of the magneto, a distributor disc rigidly carried by said coupling sleeve, a support disc detachably fitted into said casing on the side of said cover plate, said support disc having a nave projecting inwardly towards said coupling sleeve, a bush upon said nave, a rotatable cam wheel arranged on said bush and being engageable by said coupling sleeve for rotation, and at least one circuit breaker lever pivotally mounted on said support disc, the whole circuit breaker apparatus being adapted to be withdrawn together with said support disc from said casing.

2. In combination with a magneto having a casing, a cover plate arranged on one side of said casing, a coupling sleeve fitted on the rotor shaft of the magneto, a distributor disc rigidly carried by said coupling sleeve, a support disc detachably fixed to the inner side of said cover plate, said support disc having a nave projecting inwardly towards said coupling sleeve, a bush upon said nave, a rotatable cam wheel arranged on said bush and being engageable by said coupling sleeve for rotation, and at least one circuit breaker lever pivotally mounted on said support disc, the whole circuit breaker apparatus being adapted to be withdrawn together with said cover plate from said casing.

3. In combination with a magneto having a casing, a cover plate arranged on one side of said

casing and consisting of a central part and a peripheral part, being detachable from each other, a coupling sleeve on the rotor shaft of the magneto and rigidly carrying a distributor disc, a support disc detachably fixed to the inner side of said central part of the cover plate, said support disc having a nave projecting inwardly towards said coupling sleeve, a bush upon said

nave, a rotatable cam wheel arranged on said bush and being engageable by said coupling sleeve for rotation, and at least one circuit breaker lever pivotally mounted on said support disc, the whole circuit breaker apparatus being adapted to be withdrawn together with said central cover part from said casing.

WALTER OCHSENBEIN.
